Inventor:

W. B. Watkins,

WILLIAM B. WATKINS, OF JERSEY CITY, NEW JERSEY.

Letters Patent No. 88,825, dated April 13, 1869.

IMPROVED TOOTH-BRUSH.

The Schedule referred to in these Letters Patent and making part of the same.

To all whom it may concern:

Be it known that I, WILLIAM B. WATKINS, of Jersey City, State of New Jersey, have invented certain new and useful Improvements in Securing or Attaching India-Rubber Brushes for Cleaning Teeth, and other purposes, to Handles; and I do hereby declare that the following is a full description of the same.

The nature of my invention consists in forming the back of the brush with a rib or tongue, lengthways of it, of a dovetail or other suitable shape, and having an opening through it in which is inserted a piece of metal, or other hard material, so as to make the rib stiff and firm, that when inserted into the dovetail channel, cut in the lower side of the handle, it will wedge fast therein, and thus make not only a solid attachment of the brush to the handle, but also make the brush less bulky, and more easily inserted in the mouth, as well as more desirable in style of finish.

Figure 1 is a side view of the brush as secured to a handle.

Figure 2 is a longitudinal cut section of the same.

Figure 3 is cut section of the same through the line *z z*, fig. 1.

Figures 4 and 5 are an end view of the brush and handle, showing the rib on its back and channel in the handle.

Letter A represents the brush or bristles, which are formed by moulding when the rubber is in a plastic state; and

B, the back, having a rib or dovetail tongue, C, formation of rubber down its length, and stiffened by means of a piece of metal, or hard material, D, upon which the rib or tongue is formed while in the plastic state.

The object of this combination of the stiffener D with the rib, and back of the brush will be obvious, for the reason that, as the brush is of such a pliable and compressible nature, it would, in the first place, be almost impossible to insert or draw the rib into the

dovetail channel E, in the handle F, tight enough to secure the brush to the handle; and, second, that even if it could be inserted by great labor, yet it would twist out of the channel by side pressure on the brush, in consequence of its elastic properties. Therefore the stiffener D is intended for the twofold purpose of facilitating the attachment of the brush to the handle, and thus, by saving time, cheapen the cost of making the brush, and preventing the brush from getting detached from the handle by any accidental use thereof.

It will be obvious that the same method of securing the brush to the handle may be made so as to operate in transverse dovetail channels in the lower side of the handle, and though I esteem the mode of securing the brush to the handle in a longitudinal channel, as hereinbefore described, the best way to make the attachment, yet, as such transverse channels may be used, I desire it to be understood that I consider my invention to include either method as being but slight modifications of the same thing.

Having now described my invention, I will proceed to set forth what I claim, and desire to secure by Letters Patent of the United States, premising, however, that I do not claim India-rubber brushes, where the rubbers are substituted for the bristles commonly used; nor do I claim an India-rubber brush having a hollow head, in combination with a handle having a tenon on its end, as described in Thomas Maitland's patent for a tooth-brush; but

What I do claim, is—

The combination of the India-rubber brush with the handle, by means of the rib C, having a stiffener, D, in it, and dovetail channel E, in the lower side of the handle, as hereinbefore set forth.

W. B. WATKINS.
